(57) **CLAIM**

An ornamental design for a container and lid, as shown and described.

DESCRIPTION

FIG. 1 is an inverted, top perspective view of a container showing our new design;

FIG. 2 is a bottom perspective view thereof;

FIG. 3 is a top plan view thereof;

FIG. 4 is a bottom plan view thereof;

FIG. 5 is an inverted, left side elevation view thereof;

FIG. 6 is a right side view thereof;

FIG. 7 is an inverted, front side elevation view thereof; and,

FIG. 8 is a back side elevation view thereof.

The broken line portion of FIGS. 1, 3, 5, 6, 7, and 8 is included to show unclaimed subject matter only and forms no part of the claimed design.
